UNITED STATES PATENT OFFICE.

ALFRED ANDREWS, OF BARNESVILLE, OHIO.

MULTIPLE-EXPOSURE ATTACHMENT FOR CAMERAS.

1,289,357.

Specification of Letters Patent. Patented Dec. 31, 1918.

Application filed January 3, 1917. Serial No. 140,405.

To all whom it may concern:

Be it known that I, ALFRED ANDREWS, a citizen of the United States, residing at Barnesville, in the county of Belmont and

5 State of Ohio, have invented certain new and useful Improvements in Multiple-Exposure Attachments for Cameras; and I do hereby declare the following to be a full, clear, and exact description of the invention, 10 such as will enable others skilled in the art to which it appertains to make and use the same.

This invention has for its object to provide an improved multiple exposure attachment for cameras, whereby various parts of the plate or film disposed in the exposure opening may be independently exposed at the will of the photographer.

Another object is the provision of a device 20 of this character which is particularly designed for use in connection with modern types of folding cameras having the usual extensible bellows supporting the lens and shutter mechanism.

25 With these and other objects in view, the invention consists in the novel construction, combination and arrangement of parts as will be hereinafter specifically described, claimed and illustrated in the accompanying drawing, in which:

Figure 1 represents a rear elevation of a well known type of camera, showing the invention applied thereto, the removable rear plate or back of the camera being detached,

35 Fig. 2 represents a perspective view of one of the doors of the attachment removed from the camera, and

Fig. 3 represents a transverse sectional view through the door.

40 Referring to the drawing in detail, wherein similar reference numerals designate corresponding parts throughout the several views, the numeral 5 indicates a well known type of camera body having the usual film

45 spool-receiving chambers 6 at the opposite ends thereof separated by a substantially rectangular frame 7, providing the exposure opening and to which the extensible bellows 8 is attached. The usual lens support 9 and

lens 10 are secured in the front end of the 50 bellows 8 and the spool in the film-receiving chamber 6 is actuated by the usual manually operable key 11.

In applying the improved attachment to the camera a pair of parallel shafts 12 is 55 rotatably mounted in the frame 7, one shaft being located adjacent each end of the latter. Each shaft 12 supports a door, designated generally by the numeral 13, which is of approximately one-half of the size of the 60 exposure opening in the frame and may be swung to either open or closed position, as desired. Each door 13 comprises a body plate 14, preferably constructed of spring metal and tapered from end to end. The 65 relatively large end of the body plate 14 is rolled, as at 15, about the shaft 12, and is riveted or otherwise rigidly secured to the shaft for rotation therewith. The plate 14 is of such size as to permit it to be moved 70 to open position and lie snugly against one of the sides of the bellows 8, as illustrated at the left of Fig. 1, and a covering 16 of cloth, paper, or other suitable flexible material is folded over the body plate 14 and 75 constitutes the shield or screen for obscuring one-half of the film or plate disposed in the exposure opening in the camera. Owing to the inherent flexibility of the covering 16, the door 13 as an entirety, may be 80 swung to open position, and the portions of the cover 16, which project beyond the converging edges of the body plate 14 are folded against the top and bottom of the bellows 8, as clearly shown at the left of 85 Fig. 1.

Each of the shafts 12 is extended, at one end, through the top wall of the camera body 5 and is directed angularly to provide a crank or handle 17, by which the shutters 90 may be conveniently adjusted.

What I claim is:

A camera including a frame having a second frame carrying a bellows, a pair of vertical shafts journaled in the frames and 95 extending exteriorly of the camera and bent to form handles, a tapered metallic body plate secured to each of said shafts and of

such size that it will snugly fit a side of the bellows when in open position, each of said plates having flexible opaque material secured thereto and projecting beyond its upper and lower edges and beyond its end remote from its shaft to engage said second frame when said plate is in closed position and adapted to bend to conform to the top

and bottom walls of the bellows when said plate is in an open position.

10

In testimony whereof I affix my signature in presence of two witnesses.

ALFRED ANDREWS.
